COMBUSTION CONTROL

Robert A. Foresman, Prospect Park, and Donald J. Mosshart, Springfield, Pa., assignors to Westinghouse Electric & Manufacturing Company, East Pittsburgh, Pa., a corporation of Pennsylvania

Application June 25, 1936, Serial No. 87,138

8 Claims. (Cl. 137—78)

Our invention relates to control means for apparatus supplying gaseous medium to a bed offering variable flow resistance and it has for an object to provide said means so constructed and arranged that the rate of flow of gaseous medium is held substantially constant irrespective of changes in flow resistance of the bed.

A further object of our invention is to provide a duct construction for supplying gaseous medium, such as air, from a region to a bed offering variable flow resistance, the duct construction including an orifice and a throttle arranged between the orifice and the bed, the throttle including an element movable in response to change in differential pressure across the orifice due to change in flow resistance of the bed.

A further object of our invention is to provide a plurality of duct constructions for supplying gaseous medium, such as air, from a region to different areas of a bed such that each area will receive gaseous medium substantially at the constant rate even though the flow resistance of each area may vary.

These and other objects are effected by our invention as will be apparent from the following description and claims taken in connection with the accompanying drawings, forming a part of this application, in which:

Fig. 1 is a longitudinal sectional view of a stoker showing our air control devices applied thereto;

Fig. 2 is a transverse sectional view taken along the line II—II of Fig. 1;

Fig. 3 is a diagrammatic view showing a series of our control devices for a tuyère row;

Fig. 4 is a sectional view of a simplified form of device; and,

Fig. 5 is a view similar to Fig. 4 but incorporating a float.

Referring now to the drawings more in detail, in Fig. 1, we show a stoker, at 10, forming the bottom of a combustion chamber 11 and having a plenum chamber or air box 12 arranged therebelow. The plenum chamber is supplied with air through a duct 13 by the usual means, it being the intention that the plenum chamber pressure shall be maintained substantially constant and that the blower furnishing the duct 13 with air shall have adequate capacity for all operating conditions of the stoker.

The stoker includes the usual retorts 14 and intervening tuyère rows 15 and outside side wall tuyères 16. Air channels 17 are arranged below the tuyère rows 15 and the side wall tuyères 16. Transverse plates 18 preferably divide each chan-

nel 17 into a plurality of sections 19, 20, 21, and 22 supplied with air by duct constructions or devices 23, 24, 25, and 26 for each tuyère row. As shown in Figs. 1 and 2, each tuyère row air channel has connected thereto a group of devices 23, 24, 25, and 26, the devices being arranged at different levels on account of inclination of the stoker; and devices 23, 24, 25, and 26 of all the tuyères are, respectively, arranged in transverse rows, the row of devices 26 being at the front of the stoker and the other rows 25, 24, and 23 being arranged successively back thereof.

Each of the duct constructions 23, 24, 25 and 26 includes a duct element 28 and a chamber 30 at its inlet end and each chamber 30 has a body of liquid 31 therein and an orifice 32 provides for the admission of air thereto from the plenum chamber 12, the orifice being arranged above the level of liquid. Gaseous medium, such as air, admitted by the orifice 32, passes through a variable throttle area 36 before entering the duct element 28, the purpose of the orifice being to provide a differential pressure for controlling the throttle area, the arrangement being such that the throttle area is varied to compensate for variations in flow resistance of the region supplied by the duct construction. As shown in Figs. 1, 2 and 3, the orifice 32 discharges into a secondary chamber 29 formed by a downwardly-directed tubular structure or nozzle 33 whose horizontally-disposed lower end 34 cooperates with a float sustained by the liquid to provide the circumferentially-extending throttle area 36.

The level of liquid 31 in each tertiary chamber 30 is determined in the first instance by an overflow device 38 open at the top to form a well or primary chamber 39 exposed to plenum chamber pressure. Thus, it will be seen that each device has a body of liquid arranged in a monometric manner, that is, one portion is arranged within the chamber 30 and subject to secondary pressure and the other portion is arranged in the well and subject to plenum chamber pressure. As may be seen from Figs. 1 and 3, each overflow 38 is provided with means, for example, a tube arrangement 40, which is adjusted by any suitable means 41 for the purpose of adjusting the quantity of liquid and the level thereof for each device.

In the preferred form of apparatus shown in Figs. 1, 2, and 3, the flows of air in each device between the orifice 32 and the throttle 36 and from the latter, are in such directions that, with the float, 35, there is little, if any, liquid entrainment, this particular arrangement being specifi-

cally disclosed and claimed in the application of R. A. Foresman, Serial No. 84,405, filed June 10, 1936.

As air entering through an orifice 32 is discharged downwardly by the nozzle-like structure 33 against the float 35 and the air then travels upwardly through the duct to the stoker, it will be apparent that the float 35 acts as a float valve throttling the discharge of the nozzle and providing a throttling area 36 between the float and the nozzle, or a throttle as already pointed out. The float 35 is supported by the body of water within the device; and, as already pointed out, the body of water associated with each device is disposed in a manometric manner so that part thereof is subject to primary pressure P_1 and a part is arranged within the device so as to be subjected to secondary pressure P_2 , as may be seen from the duct construction 24 in Fig. 3. As a matter of fact, the body of liquid in the chambers 30 of Figs. 1, 2, and 3 is subject to both secondary and tertiary pressures, P_2 and P_3 , that is, the pressures at the upstream and downstream sides of the throttle area 36.

Changes in the pressure differential across the orifice 32 causes the liquid level within the chamber 30 to rise or fall to vary the throttle area, an increase in the differential causing the liquid to rise and vice versa. Assuming that this differential ($P_1 - P_2$) increases, then the float 35 rises, reducing the throttle area 36; and, in consequence, a second pressure differential ($P_2 - P_3$), the difference between secondary and tertiary pressure, is set up across the throttle 36 and which imposes the difference of primary and tertiary pressure ($P_1 - P_3$) upon the water within the device, causing a further rise of the water therein and a further lift of the float.

Thus, it will be seen that the float 35 and the manometric body of liquid supporting it comprise the lower and movable element of the throttle, such element being inherently capable of providing a force acting in opposition to the force of the pressure at the inlet side of the orifice, whereby the movable element may be moved by the various forces acting thereon to different positions to restore approximately the rate of flow of air through the device in case of variation in fuel bed resistance. With the float in equilibrium, the forces thereon are the upwardly acting lift force of the water, it being remembered that the float is positioned primarily by the extent of rise or fall of the manometric leg of water sustaining it, the downwardly acting static secondary pressure P_2 and the impact of the air stream passing through the throttle area from the secondary to the tertiary pressure regions, such impact being a function of P_2 minus P_3 . Aside from the manner of response of the manometric column of liquid to the various pressures, resulting in movement of such column, and, therefore, of the float, the effect of the lift of the liquid on the float is, of course, also a function of its shape, that is, its displacement. Furthermore, an additional control of the reactions of each device may be obtained by varying the initial value of the throttle area, this providing an initial pressure differential between secondary and tertiary pressures ($P_2 - P_3$) before the device begins to respond to changes in the rate of air flow. The upward and downward forces acting on the float 35 are brought into balance by proportioning the displacement of the float and the area subject to impact and static air pressure. Once the forces are balanced, the

lower movable throttle element, comprising the liquid and the float, functions to maintain a substantially constant rate of air flow through the device irrespective of changes in fuel bed resistance of the region or area supplied thereby. In general, the lower movable throttle elements have liquid-sealed pressure abutment faces subject to pressures at the inlet and exit sides of the orifice, such pressures providing opposed forces acting on the element to afford movement thereof and to vary the throttle area, and the throttle is inherently capable of providing a gravity force, which, with the force due to the pressure at the exit side of the orifice, balances the force due to the pressure at the inlet side of the orifice; and, while these are the main forces acting in opposition to effect equilibrium of the movable element, nevertheless, there may be other forces exerting an effect on the movable element, such forces being that due to the tertiary pressure and the impact force effective in the arrangement shown in Fig. 1.

It is desirable to maintain predetermined quantities or levels of liquid in each device, this being determined by appropriate adjustment of the overflows in the manner already indicated. It is also necessary to replenish each device with water, that is, to keep the overflows thereof filled to the point of overflow. Accordingly, in Figs. 1, 2, and 3, we show an arrangement for effecting this purpose. Each transverse group of chambers 30 are connected in series by means of the nipples 50 and cooperating couplings 51, the intermediate chamber 30 extending below the others to provide a hopper 52 for a purpose to be immediately pointed out. If water is supplied by means of the inlet conduit 53, as shown in Figs. 1 and 3, to one of the devices 26, it will be apparent that all of the devices of that group will be supplied with water through the nipples and the couplings. Furthermore, a single overthrow is adequate to maintain a desired level of liquid in that group of devices.

The conduit connections 54, 55, and 56 from the overflow of a preceding transverse group, beginning with the group 26, and one of the intermediate chambers of the next group provide for a cascade connection of the groups so that a single water supply connection 53 and a single drain conduit 57, for the last transverse group, suffice to keep all of the devices adequately supplied with water.

There is also shown suitable means for flushing out all of the devices, this means being more particularly described and claimed in the application of D. J. Moss hart, Serial No. 85,861, filed June 18, 1936, such means comprising drain branches 58 associated with the hoppers or sumps 52 of intermediate devices, as already pointed out, the drain branches being connected to a drain pipe 59 and each drain branch having a valve 60. As may be seen from Fig. 2, opposite water jets 62 are associated with the outermost chambers 30, the jets being supplied by water pipes 63 having valves 64. With this arrangement, if the valves 60 are opened to the desired extent, and the jets 62 are rendered effective, it will be apparent that such jets will entrain liquid and solid media from the chambers from each side toward the central hopper, this being made possible by alignment of the nipples and couplings of each group of devices whereby the jet streams will be directed therealong from each side and toward the hopper, and media will drain 75

from the hopper or hoppers through the conduit 59.

While it is intended that the pressure, P_1 , of the chamber or windbox shall be maintained substantially constant, it may be necessary to effect changes in flow of air through the various devices to take care of different load conditions. Accordingly, each orifice 32 has associated therewith a valve or gate 65 for varying its area, the gate valves being connected to operating rods 66, whose lower ends are pivotally connected to cranks 67 of the crank shaft 68. The crank shafts 68 have cranks 69, each provided with a plurality of openings 70 arranged at different radial distances from the axis of the crank shaft 68, and links 71, having turnbuckles 72, have their ends pivotally connected to the cranks 69, each link 71 being suitably adjusted in length and connected to openings to secure the desired relative extent 20 of operation of the gate valves 65 of the different transverse groups of air control devices. The interconnected arrangement of crankshafts may be operated by manual or automatic means, for example, the load-responsive combustion control 25 device, as shown at 74, this device being connected by means of linkage 75 to the first of the crank shafts 68. As shown, the linkage at 75 embodies a link 76 having a turnbuckle 77 and such link being pivotally connected to the first crank 69 and associated with one of the openings 70 therein. From this, it will be apparent that all of the gate 30 valves may be changed relatively to the load responsive device 74 by suitable connection of the link 76 with the first crank 70; and, as already 35 pointed out, the gate valves of the devices of the various groups may all be adjusted to the same extent or they may be adjusted to different extents, the capacity for relative variation being provided for by the links 71 of variable length and the connections of the ends thereof to any of the 40 openings 70 in the cranks 69.

In Fig. 4, there is shown a simplified form of duct construction, which differs over that already described mainly in that the nozzle is arranged 45 between the chamber 30 and the duct 28 rather than between the orifice and the chamber, as in Figs. 1, 2 and 3. In the modified form, the duct 28 has a tubular structure 42a depending within the chamber 30, the latter having an orifice 32 for admitting air from the windbox to the secondary chamber for passage through the associated 50 circumferential throttle area 45 and duct 28. A well or primary chamber 39 exposed to the plenary or windbox pressure has its bottom portion connected to the bottom portion of the chamber 30 by an opening 43, whereby the chambers 39 and 30 provide a manometric chamber. A sufficient quantity of liquid 31 is placed in the chamber 30 and in the well 39 to keep the opening 43 submerged under all conditions. Accordingly, there is provided a manometric arrangement of liquid, the first part being in the well 39 and exposed to plenary or primary air pressure P_1 , and a second part being in the chamber 30 and subject to secondary pressure P_2 . The level 55 of liquid 44 cooperates with the lower end 42 of the tubular element 42a to provide a circumferentially-extending throttle area 45. As before, the change in differential pressure across the 60 orifice 32 incident to change in flow resistance of the region supplied by the duct 28 brings about change in liquid level to vary the throttle area so as to compensate for change in flow resistance of the region.

In Fig. 5, there is shown a modified form simi-

lar to Fig. 4 except that a float 46 is sustained by the liquid and it cooperates with the tubular element to define the annular orifice area 45a, which changes with changes in level 44a of the liquid.

From the foregoing, the effect and operation of our improved apparatus will be apparent. First of all, there is a region of variable flow resistance, such as a fuel bed, to be supplied with gaseous medium such as air, and the object of the invention is the provision of one or more ducts or devices for supplying gaseous medium from a chamber under suitable pressure to the region, each duct or device including arrangements to maintain the flow rate substantially constant irrespective of changes in flow resistance of the particular region supplied. The arrangements making this result possible comprise primarily an inlet orifice for admitting gaseous medium from the chamber to the duct or device and a throttle arranged in the duct and following the device, the throttle including fixed and movable elements defining a variable throttle area and the movable element being constructed and arranged to provide pressure abutment faces subject to the pressures at the inlet and exit sides of the orifice and to provide a force, in addition to the pressure forces, and all of the forces being necessary to produce a condition of equilibrium of the movable element. The additional force just referred to is preferably inherent in the movable element, that is, it may be a gravity force which is made available by the construction and arrangement of the movable element. The movable element comprises a body of liquid and a manometric chamber to give form and to confine the body in such a way that a gravity force is made available for the purpose just indicated, and the liquid so disposed presents sealed pressure abutment faces subject to pressures at the inlet and exit sides of the inlet orifice, an equilibrium condition being produced by the gaseous pressure forces acting on the abutment faces and the gravity force acting on the body, all of these forces cooperating to determine movement of the movable body element to that necessary to restore equilibrium following the occurrence of an unbalanced condition. The additional force afforded by the gravity effect finds its counterpart in many kinds of control apparatus, that is, in the present invention, the movable throttle element is so constructed and arranged that it inherently provides a balancing force cooperating with the gaseous pressure forces to produce an equilibrium condition; and, when an unbalanced condition occurs, as by change in differential pressure, the movable element moves in consequence, but such movement is affected or determined by the gravity force, and, as movement of the movable element occurs in such a direction as to tend to restore the differential pressure, the gravity and orifice exit side pressure forces changing in opposite directions operate to restore the equilibrium condition, at which time the gravity and exit side pressure forces balance the inlet side pressure force and the differential pressure is brought back approximately to its normal value.

By having a multiplicity of ducts or devices of the character just indicated and connected to different regions of the fuel bed, and as each duct or device includes contrivances to maintain the rate of flow of air therethrough substantially constant irrespective of the flow resistance, of the regions supplied thereby, irregular fuel bed con-

ditions are compensated for by various ducts or devices in such manner that the fuel bed has a better opportunity to restore itself and to be maintained in a more nearly desired average condition. Furthermore, the several duct constructions are structurally and functionally independent, each including a meter or control element in the form of an orifice, the change in the pressure difference across which results in change 10 of the associated throttle area in such a direction as to restore the normal differential, and, therefore, the normal rate of flow. As the orifice is a plain opening into the duct construction and as the throttle and its operating mechanism are entirely enclosed within the duct construction without protrusion of moving parts into the air box, there results an arrangement peculiarly suitable to meet conditions encountered in stoker practice in that derangement of the mechanism on 20 account of ash is reduced to a minimum.

While we have shown our invention in several forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

30. What we claim is:

1. In apparatus for supplying air to a flow-resisting bed, means providing an air box supplied with air under desired pressure, a plurality of chambers arranged in a plurality of rows extending 35 transversely of the bed, ducts for supplying air from the chambers to different areas of the bed, orifices for admitting air from the box to the chambers, throttles for controlling the flow of air from the chambers and through the ducts to the bed and each throttle including means responsive to differences in air pressure in its associated chamber with respect to air box pressure to control the throttle area, and means providing for area variation of the orifices of the 40 respective rows of chambers to the same extent and of the orifices of the chambers of different rows to different desired extents.

2. In apparatus for supplying air to a flow-resisting bed, means providing an air box supplied 50 with air under suitable pressure, an air chamber, a duct for supplying air from the chamber to the bed, means providing a manometric body of liquid with one leg portion subject to the air pressure in the chamber and the other leg portion subject to air pressure of the box, an orifice for admitting air from the box to the chamber, and means providing a throttle controlling the flow of air from the chamber to the bed, said last-named means including a float which is moved by 55 changes in liquid level of the leg subject to chamber pressure to vary the throttle flow area.

3. In apparatus for controlling the flow of gaseous medium from a first region maintained under suitable pressure to a second region of variable flow resistance, a duct for supplying gaseous medium to the second region; an orifice for admitting gaseous medium from the first region to the duct; and a throttle having its flow area in the duct and arranged in the path of flow between 65 the orifice and the second region; said throttle including a tubular element forming a part of the flow passage and having a horizontally disposed lower end, means providing a U-shaped space having a first leg whose upper portion is 70 open to said first region and a second leg whose

upper portion is arranged vertically below the lower end of said tubular element and is open to the interior of said duct, and a body of liquid in said space and whose level in the second leg cooperates with the lower end of the tubular 5 element to provide the throttle area.

4. In apparatus for controlling the flow of gaseous medium from a first region maintained under suitable pressure to a second region of variable flow resistance, a duct for supplying gaseous medium to the second region; an orifice for admitting gaseous medium from the first region to the duct; and a throttle having its flow area in the duct and arranged in the path of flow between the orifice and the second region; said 10 throttle including a tubular element forming a part of the flow passage and having a horizontally-disposed lower end, means providing a U-shaped space having a first leg whose upper portion is open to said first region and a second leg 15 whose upper portion is arranged vertically below said lower end of the tubular element and is open to the interior of said duct, a body of liquid in said space, and a float sustained by the liquid in the second leg; said float cooperating with said 20 lower end of the tubular element to define the throttle area and the level of liquid in said second leg determining the throttle area.

5. In apparatus for controlling the flow of gaseous medium from a first region maintained under suitable pressure to second region of variable flow resistance, a duct for supplying gaseous medium to the second region; an orifice for admitting gaseous medium from the first region to the duct; a throttle having its flow area arranged in 30 the path of flow between the orifice and the second region; said throttle including a tubular element forming a part of the flow passage and having a horizontally-disposed lower end, means providing a U-shaped space having a first leg whose upper portion is open to said first region and a second leg whose upper portion is arranged vertically below said lower end of the tubular element and is open to the interior of said duct, and a body of liquid in said space and whose level in the second leg cooperates with the lower end of the tubular element to provide the throttle area; and means providing for adjustment of the area of the orifice.

6. In apparatus for controlling the flow of gaseous medium from a first region maintained under suitable pressure to a second region of variable flow resistance; a duct for supplying gaseous medium to the second region; an orifice for admitting gaseous medium from the first region to the duct; a throttle having its flow area arranged in the path of flow between the orifice and the second region; said throttle including a tubular element forming a part of the flow passage and having a horizontally-disposed lower end, means providing a U-shaped space having a first leg whose upper portion is open to said first region and a second leg whose upper portion is arranged vertically below said lower end of the tubular element and is open at its top to the interior of said duct, and liquid in said space and cooperating with said tubular element to provide the throttle area, said orifice being arranged above the liquid in order that the latter may be subject to the differential pressure across the orifice to control the throttle area; means for supplying liquid to said space; and an overflow for discharging excess liquid from said first leg.

7. In apparatus for controlling the flow of gaseous medium from a first region maintained 75

under suitable pressure to a second region of variable flow resistance; a duct for supplying gaseous medium to the second region; an orifice for admitting gaseous medium from the first region to the duct; a throttle having its flow area arranged in the path of flow between the orifice and the second region; said throttle including a tubular element forming a part of the flow-passage and having a horizontally-disposed lower end, means providing a U-shaped space having a first leg whose upper portion is open to said first region and a second leg whose upper portion is arranged vertically below said lower end of the tubular element and is open to the interior of said duct, and liquid in said space and cooperating with said tubular element to provide the throttle area, said orifice being arranged above the liquid in order that the latter may be subject to the differential pressure across the orifice to control the throttle area; means for supplying liquid to said space; and a vertically adjustable

overflow associated with the first leg for discharging excess liquid from said space.

8. In apparatus for controlling the flow of gaseous medium from a first region maintained under suitable pressure to a second region of variable flow resistance, a duct for supplying gaseous medium to the second region and having a chamber at its inlet end; an orifice for admitting gaseous medium from the first region to the chamber; means providing a throttle in the chamber and comprising a vertically disposed tubular element forming a portion of the flow passage for gaseous medium and a body of liquid whose upper surface is normally spaced from the lower end of the tubular element to define the throttle area; and means responsive to differential pressure across the orifice for controlling the level of said liquid.
